Des. 204,926
Patented May 24, 1966

204,926

LOOM PICK ARM

Florence F. Donoghue, Worcester, Mass., assignor to
Draper Corporation, Hopedale, Mass., a corporation of
Maine

Filed Aug. 19, 1965, Ser. No. 86,645

Term of patent 14 years

(Cl. D92—15)

FIG. 4

FIG. 5

FIG. 6

FIG. 1 is a top plan view of a loom pick arm showing my new design;

FIG. 2 is a side elevational view thereof;

FIG. 3 is a bottom plan view;

FIGURE 4 is a sectional view taken on line 4—4 of FIGURE 3;

FIGURE 5 is an end view as seen from the left side of FIGURE 3; and

FIGURE 6 is an end view as seen from the right side of FIGURE 3.

I claim:

The ornamental design for a loom pick arm, substantially as shown.
